UNITED STATES PATENT OFFICE

BRUNO BERNEIS, OF NUERMBERG, GERMANY, ASSIGNOR TO THE FIRM VEREINIGTE SCHUHFABRIKEN BERNEIS-WESSELS A.-G., OF AUGSBURG-OBERHAUSEN, GERMANY

TURN CAMEL HAIR SHOE WITH FELT AND LEATHER SOLE AND WITH SOLID HEEL COUNTER

Application filed July 8, 1929, Serial No. 376,746, and in Germany July 12, 1928.

The turn camel hair shoes with felt- and leather sole found on the market have usually no counter and a soft bolstered covering insole which is stitched in. These so called 5 run-down heel shoes are flexible in the heel end of the arch and ball of the foot.

Turn camel hair shoes with solid counter are manufactured which are fitted however over the whole length with a stiff covering insole impeding the flexibility in the ball and in the heel end of the arch.

The turn camel hair shoe with felt- and leather sole according to the invention combines the advantages of a flexible sole and 15 those of a solid counter. The novelty of the turn camel hair shoe with felt- and leather sole and with solid counter according to the invention consists in that the bolstered covering insole has a glued in stiff support only 20 from the rear end to the heel end of the arch, being soft and stitched in from the heel end of the arch to the toe point of the shoe so that the shoe with solid heel counter is flexible in the heel end of the arch and in the 25 ball, detaching shifting and creasing of the bolstered covering insole being prevented.

An embodiment of the invention is illustrated by way of example in the accompanying drawings in which:

30 Fig. 1 is a longitudinal section,

Fig. 2 is a section on line A—B of Fig. 1 the covering insole being shown in top plan view and

Fig. 3 a section on line C—D of Figs. 1 35 and 2.

a is the felt sole, b the leather sole and c, d the ulster-like camel-hair cloth. The heel portion has a stiff counter. Between the heel lining f and the layer d' of cloth a 40 stiff counter g is inserted and glued in. On the edge f' of the heel lining resting upon the edge g' of the piece of buckram a stiff sole h is glued, as in these known camel hair shoes, onto which by a seam i the soft covering sole l, enclosing a bolster k, is sewn.

While in the known turn camel hair shoes with solid counter the stiff sole extends from the heel to the toe, it extends according to the present invention only to the heel end of 50 the arch n. From this heel end of the arch

n along the ball portion o up to the toe point m only the soft covering insole l lies on the bolster k and is stitched with a seam p onto the edge d'' of the camel hair cloth. This seam p extends from the toe to the heel end of 55 the arch.

As shown, the new camel hair shoe combines the advantages of the two kinds of turn camel hair shoes on the market without possessing their inconveniences. The new shoe 60 has a stiff support only on the heel and a stiff counter, the free movability and the elasticity of the foot joint and of the ball is not impeded in the least.

I claim:—

65 A turn camel hair shoe with felt- and leather sole and with solid heel-counter, comprising in combination with the felt sole, a bolster-insert sole extending from the toe end to the rear heel edge and stitched in from the ball line to the toe end, the bolster in said 70 stitched part bearing directly on said felt sole, and a stiff insert on which said bolster-insert sole is stitched from the ball line around the whole edge of the heel part resting 75 upon the flat shoe heel, said stiff insert being inserted from the rear and from below said bolster with its front edge, extending to approximately one quarter of the total length of 80 said bolster, which over this area is thinner than the remaining part, said stiff insert being connected by glueing to the bolster-covering and also to the felt sole.

In testimony whereof I affix my signature.

BRUNO BERNEIS.
